UNITED STATES PATENT OFFICE.

THOMAS L. THOMPSON, OF KINGFISHER, OKLAHOMA.

CHURN.

1,083,158.

Specification of Letters Patent.

Patented Dec. 30, 1913.

Application filed July 3, 1913. Serial No. 777,320.

To all whom it may concern:

Be it known that I, THOMAS L. THOMPSON, a citizen of the United States, residing at Kingfisher, in the county of Kingfisher 5 and State of Oklahoma, have invented certain new and useful Improvements in Churns; and I do declare the following to be a full, clear, and exact description of the invention, such as will enable others skilled 10 in the art to which it appertains to make and use the same.

This invention relates to improvements in churns and particularly to working body churns.

15 One object of the invention is to provide a churn of this character having an improved construction and arrangement of a resilient body supporting mechanism whereby the body of the churn may be rapidly vibrated or sprung upwardly and downwardly thus thoroughly agitating the cream and quickly turning the same into butter.

Another object is to provide means for 25 regulating the tension of the resilient body supporting mechanism whereby the body may be operated more or less freely.

With these and other objects in view, the 30 invention consists of certain novel features of construction, and the combination and arrangement of parts as will be more fully described and claimed.

In the accompanying drawings: Figure 1 is a perspective view of my improved 35 churn; Fig. 2 is a central vertical longitudinal section thereof; and Fig. 3 is a horizontal section taken on the line 3—3 of Fig. 2.

My improved churn comprises a body 1 40 which may be of any suitable size and shape but which is preferably in the form of a cylindrical can having in its upper end an opening 2 which is adapted to be closed by a tight fitting cover 3. Rigidly secured to one side of the body 1 is a vertically disposed sleeve or tube 4 which is adapted to receive the outer ends of the body supporting mechanism hereinafter described.

The body supporting mechanism herein 50 referred to comprises upper and lower spring metal bars 5 and 6 the inner ends of which are bent at right-angles to form attaching members 7 which are adapted to be secured in any suitable manner to any 55 suitable support 8 said support being shown in the present instance as an upright post

to the lower end of which are secured two diverging feet 9 which are of sufficient length to provide a firm support for the churn while being operated.

The bars 5 and 6 are spaced apart to a distance corresponding to the length of the sleeve or tube 4 on the body of the churn and the free end of the upper bar 5 is bent downwardly at right-angles to form a body attaching lug 10 while the free end of the lower bar is bent upwardly to form a body attaching lug 11. The lugs 10 and 11 are engaged respectively with the upper and lower ends of the sleeve 4.

70 The lugs 10 and 11 are securely held in engagement with the ends of the sleeve 4 by a combined clamping and tension bolt 12 which is engaged with alined apertures formed in the upper and lower bars 5 and 6 near their free ends as shown. The bolt 12 is provided on its lower end with a head 13 and on its threaded upper end with a tension nut 14 which is screwed downwardly on the bolt and into engagement with the 80 upper bar 5. By arranging the bolt 12 as herein shown and described it will be seen that the lugs 10 and 11 will be securely held in operative engagement with the ends of the sleeve 4 and by providing the bolt with 85 the clamping nut 14, it will be seen that the outer portions of the bars 5 and 6 may be more or less tightly connected or held more or less rigid thus regulating the tension or spring action of the bars and thereby permitting the body of the churn to be vibrated 90 more or less freely.

95 By constructing and arranging the body supporting mechanism of the churn as herein shown and described, it will be seen that in order to operate the latter, it is simply necessary to impart slight pressure to the top of the body or to the outer ends of the supporting bars whereby the body of the churn will be rapidly vibrated or swung 100 up and down and thus agitating the cream and quickly turning the same into butter.

105 In order to facilitate the churning action of the cream, the body of the churn has preferably arranged therein, a dasher or agitating mechanism which is herein shown and is preferably in the form of a wire coil 15 of suitable size, which is of uniform dimensions throughout its entire length and conforms to the entire length of the inner cylindrical surface of the body 1, which coil 110 extends from the bottom to the top of the

body and through the coils of which the cream is forced by the reciprocating or vibratory movement of the churn body.

By constructing and arranging my invention 5 proved churn as herein already shown, it will be seen that the same may be easily operated and a maximum movement obtained for the body of the churn from a minimum amount of effort or exertion on 10 the part of the operator.

From the foregoing description, taken in connection with the accompanying drawings, the construction and operation of the invention will be readily understood without requiring 15 a more extended explanation.

Various changes in the form, proportion and the minor details of construction may be resorted to without departing from the principle or sacrificing any of the advantages 20 of the claimed invention.

Having thus described my invention what I claim is:

1. A churn comprising a cylindrical body having thereon a sleeve extending the entire 25 length of said body, a support, resilient bars having one end of each permanently secured

to said support and having their opposite ends bent inwardly for detachable engagement with the opposite open ends of the sleeve, and a tension bolt passing through 30 said resilient bars and provided with a nut whereby said bars are more or less rigidly connected and the tension thereof regulated.

2. A churn comprising a cylindrical body and a removable cover therefor, a dasher 35 removably arranged therein and comprising a wire coil of uniform dimensions throughout its entire length and closely engaged with the inner surface of the body, the opposite ends of said coil being disposed between the bottom of said body and the removable cover therefor, supporting bars connected at their free ends with the body of the churn, and means to regulate the spring action of the bars.

In testimony whereof I have hereunto set my hand in presence of two subscribing witnesses.

THOMAS L. THOMPSON.
